RECEIVER CIRCUIT-ARRANGEMENT FOR
LOW-FREQUENCY OR CARRIER WAVE
TELEPHONY SYSTEMS

Johannes Ensink, Eindhoven, Netherlands, assignor to Hartford National Bank and Trust Company, Hartford, Conn., as trustee

Application January 23, 1948, Serial No. 3,964
In the Netherlands February 21, 1947

5 Claims. (Cl. 179—1)

1

As is well-known, in telephony systems not only speech currents, which may be understood to include music, but also dialling and calling signals and the like are required to be transmitted.

At the transmitter end these signals have the character of direct current impulses, but in carrier-wave telephony systems and also in low-frequency systems, in which transmission is effected through pupinised cables, are converted into alternating current impulses, each impulse being built up from a number of periods of a low-frequency or high-frequency oscillation, then they are transmitted. At the receiver end these impulses must be re-converted into direct current impulses.

The invention relates to a receiver circuit-arrangement for low-frequency or carrier-wave systems for amplifying low-frequency speech currents and for receiving signalling impulses having a frequency in the speech-frequency band.

In the present case the transmitted impulses are consequently built up from a number of periods of an oscillation, the frequency of which is included in the speech-frequency band of, for example, from 300 to 3000 c/s and is, for example 2500 c/s.

These signalling impulses must therefore be separated at the receiver end from speech currents to wit in such manner as to prevent signalling impulses from inducing interference in the transmitted conversation and, on the other hand, oscillations of 2500 c/s in the speech currents from inducing interference in signalling.

In an arrangement according to the invention, the incoming signal is fed to the input circuit of a discharge tube, from the output circuit of which the speech currents are abstracted; this output circuit has coupled to it a circuit tuned to the frequency of the signalling impulses and a circuit including a rectifier and connected in series therewith a parallel combination of a resistance and a capacity, the voltages set up across the tuned circuit and across the parallel-combination being combined in such manner and being supplied in such manner to a second rectifier with which is connected in series a second parallel combination of a resistance and a capacity, which combination is included in the input circuit of the discharge tube, that on reception of signalling impulses a relay which controls a signal-current circuit and which is included in the output circuit of the tube becomes operative.

In order that the invention may be more clearly understood and readily carried into effect, it will now be described more fully with reference to the

2

accompanying drawing, in which one embodiment thereof is shown by way of example.

The incoming low-frequency signals are fed through terminals 1 and 2 and a transformer 3 to the input circuit of a discharge tube 4. As long as signalling impulses do not occur, this discharge tube operates somewhere at the centre of its grid-current anode-voltage characteristic curve and the speech currents, in some cases

music, are abstracted from the secondary of a transformer 5.

Through transformers 6 and 7, which, as an alternative, may be combined to form a single transformer comprising one primary and two secondary windings, the output circuit of the pentode 4 has in addition coupled to it the circuit 8 tuned to the signalling impulses, for example to 2500 c/s, and the rectifier circuit 9.

Upon supply of a signalling impulse to the input terminals 1, 2, a high alternating voltage is set up across the circuit 8 and a direct voltage having a polarity as shown in the drawing is set up across the parallel-combination of resistance 10 and capacity 11.

These voltages are combined and supplied through rectifier 12 to the parallel-combination of resistance 13 and capacity 14 included in the input circuit, the voltage across the parallel-combination 10, 11 having a blocking effect on the rectifier 12 so that the latter only allows current to pass, if a signalling impulse is fed to the input terminals 1, 2 with the result that the circuit 8 has set up across it a voltage which exceeds the blocking voltage. Supply of voltages of

speech currents having a frequency different from 2500 c/s results in a blocking voltage and if occasionally a speech-current frequency of 2500 c/s occurs, the condenser 11 is charged comparatively rapidly by way of the small resistance of the rectifier and the voltage across the tuned circuit has not yet been exhausted to the required higher voltage.

On reception of a signalling impulse the parallel-combination 13, 14 has set up across it a voltage of the polarity indicated in the drawing. Consequently the discharge tube is substantially cut off, owing to which the direct current in the output circuit is decreased to the extent of the signalling relay 15 included in this circuit and controlling the signal-current circuit being de-energized and this enables a direct current impulse to be set up in the said signal current circuit.

Termination of the signalling impulse results in damping of the oscillation across the circuit

8, so that the voltage across this circuit is decreased whilst with properly chosen time-constant of the parallel-combination 10, 11, for example 50 milliseconds the cut-off voltage subsists for some more time. In contradistinction to this the time-constant of the parallel-combination 13, 14 is chosen to be small, for example 2 msec. so that the voltage occurring across is decreased very rapidly, with the result that the pentode 4 is again ready for amplifying speech current signals.

In a favourable form of the circuit-arrangement according to the invention the input circuit of the discharge tube has set up across it a negative bias voltage which is taken from a capacity to which the voltage set up across a resistance included in the cathode lead of the discharge tube is fed through a rectifier which is cut-off on reception of signalling impulses.

The negative bias voltage is taken from the capacity 17. This is charged with the aid of the voltage set up across the resistance which is included in the cathode lead and with which a small part 17 of the potentiometer connected to the source of supply voltage is connected in series.

As long as signalling impulses do not occur, there is set up by the anode-direct anode current of the tube 4 across the resistance 18 a voltage drop which exceeds the voltage across the resistance 19, which voltage has a blocking effect. The capacity 17 is then charged by way of the rectifier 20. On reception of signalling impulses at which the direct anode current is very small, the rectifier 20 is blocked.

This generated negative bias voltage has the effect of substantially obviating any variation in value of the anode current on replacement or change of the discharge tubes.

It is well to note that the generated negative bias voltage should preferably not change upon the occurrence of signalling impulses, so that the time-constant of the network used for producing these voltages should exceed the time period of the longest impulse that occurs of the order of 400 msec.

In this case the usual parallel-combination of resistance and capacity cannot be used, since this requires either a high capacity value, which is undesirable in view of the space available in telephony receivers, or involves the use of a high resistance value.

The latter requirement is also undesirable, since the secondary electron-emission which is always evolved by the control-grid may have the effect of setting up a positive control-grid voltage, whilst the control-grid circuit already comprises a comparatively heavy resistance 13.

Thus the circuit-arrangement shown ensures that in the conductive direction of the rectifier when the latter exhibits an internal resistance of the order of magnitude of $10,000 \Omega$ a positive grid-current will not occur and in the other direction, when the internal resistance is of the order of magnitude of $30 M \Omega$ a large time-constant is obtained.

It will be obvious that the circuit-arrangement according to the invention dispenses with alarm relays as used in the known circuit-arrangement, since the signalling relay 15 operates as such. In the case of the operating voltages of the tube 4 being reduced or failing, this relay becomes operative.

What I claim is:

1. A telephone receiving system for selectively amplifying audio currents and intercepting sig-

nal pulses formed by oscillations whose frequency lies within the audio range, said system comprising an electron discharge tube including a cathode, a grid and an anode, means coupled to said grid for applying the audio currents and the signal pulses thereto, means coupled to said anode for deriving amplified audio currents therefrom, a resonant network coupled to said anode and tuned to the frequency of said signal pulses, a first resistance-capacitance parallel circuit, a first rectifier, means coupling said first circuit through said first rectifier to said anode to charge said first circuit, a second resistance-capacitance parallel circuit, a second rectifier, means connecting said resonant network in series with said first circuit through said second rectifier across said second circuit to charge said second circuit solely when an oscillatory voltage is developed across said resonant network, means to apply the voltage developed across said second circuit to said grid to render said tube non-conductive during the existence of signal pulses, and means coupled to said anode and responsive to the non-conduction of said tube to produce output signal pulses in accordance with said input signal pulses.

2. A telephone receiving system for selectively amplifying audio currents and intercepting signal pulses formed by oscillations whose frequency lies within the audio range, said system comprising an electron discharge amplifying tube including a cathode, a grid and an anode, an input circuit coupled to said grid for applying the audio currents and the signal pulses thereto, an output circuit coupled to said anode for deriving amplified audio currents therefrom, a resonant network coupled to said output circuit and tuned to the frequency of said signal pulses, a first blocking voltage resistance-capacitance parallel circuit connected in series with said resonant network, a first rectifier, means coupling said first blocking voltage circuit through said first rectifier to said output circuit to charge said first blocking voltage circuit, a second blocking voltage resistance-capacitance parallel circuit, a second rectifier, means connecting said serially-connected resonant network and said first circuit through said second rectifier across said second blocking voltage circuit to charge said second blocking voltage circuit solely when an oscillatory voltage is developed across said resonant network, means to apply the voltage developed across said second blocking voltage circuit to said input circuit to render said tube non-conductive during the existence of signal pulses, and means coupled to said output circuit and responsive to the non-conduction of said tube to produce output signal pulses in accordance with said input signal pulses.

3. A telephone receiving system for selectively amplifying audio currents and intercepting signal pulses formed by oscillations whose frequency lies within the audio range, said system comprising an electron discharge tube including a cathode, a grid and an anode, an input circuit coupled to said grid, means to apply said audio currents and said signal pulses to said input circuit, an output circuit coupled to said anode, a signal relay having an energizing winding, first and second coupling transformers each having a primary and a secondary, means to apply an anode potential through said output circuit in series with said relay winding and the primaries of said first and second coupling transformers to said anode whereby said relay is energized during the conduction of said tube, a condenser con-

nected in parallel with the secondary of said first transformer to define therewith a resonant network tuned to the frequency of said signal pulses, a first resistance-capacitance parallel circuit, a first rectifier connected in series with said first circuit across the secondary of said second coupling transformer, said first circuit and said resonant circuit being connected in series, a second resistance-capacitance parallel circuit, a second rectifier, and means to connect said serially-connected resonant network and said first circuit through said second rectifier across said second circuit, said first circuit applying a bias across said second rectifier which is overcome by the oscillatory voltage developed across said resonant network solely during the existence of signal pulses to charge said second circuit, and means to apply the voltage developed across said second circuit to said input circuit to render said tube non-conductive during the existence of signal pulses, thereby to deenergize said relay.

4. A telephone receiving system for selectively amplifying audio currents and intercepting signal pulses formed by oscillations whose frequency lies within the audio range, said system comprising an electron discharge amplifying tube including a cathode, a grid and an anode, an input transformer having a primary and a secondary one end of which is connected to said grid, means to apply said audio currents and said signal pulses to the primary of said input transformer, an output transformer having a primary one end of which is connected to said anode and a secondary, a signal relay having an energizing winding, first and second coupling transformers each having a primary and a secondary, means to apply an anode potential to the other end of the primary of said output transformer through said relay winding in series with the primaries of said first and second coupling transformers whereby said relay is energized during the conduction of said tube, a condenser connected in parallel with the secondary of said first transformer to define therewith a resonant network tuned to the frequency of said signal pulses, a first blocking voltage resistance-capacitance parallel circuit, a first rectifier connected in series with said blocking voltage circuit across the secondary of said second coupling transformer, said first blocking voltage circuit and said resonant circuit being connected in series, a second blocking voltage resistance-capacitance parallel circuit having one terminal thereof connected to the other end of the secondary of said input transformer and the other terminal thereof coupled to said cathode, a second rectifier, and means to connect said serially-connected resonant network and first blocking voltage circuit through said second rectifier across said second blocking voltage circuit, said first blocking voltage circuit applying a bias across said second rectifier which is overcome by the oscillatory voltage developed across said resonant network solely during the existence of signal pulses to charge said second blocking voltage circuit thereby to apply a cut-off bias to said tube and deenergize said relay in the anode circuit thereof.

5. A telephone receiving system for selectively amplifying audio currents and intercepting signal pulses formed by oscillations whose frequency lies

within the audio range, said system comprising an electron discharge amplifying tube including a cathode, a grid and an anode, an input transformer having a primary and a secondary, one end of which is connected to said grid, means to apply said audio currents and said signal pulses to the primary of said input transformer, an output transformer having a primary one end of which is connected to said anode and a secondary, a signal relay having an energizing winding, first and second coupling transformers each having a primary and a secondary, a source of anode potential having the positive terminal thereof connected to the other end of the primary of said output transformer through said relay winding in series with the primaries of said first and second coupling transformers whereby said relay is energized during the conduction of said tube, a condenser connected in parallel with the secondary of said first transformer to define therewith a resonant network tuned to the frequency of said signal pulses, a first blocking voltage resistance-capacitance parallel circuit, a first rectifier connected in series with said blocking voltage circuit across the secondary of said second coupling transformer, said first blocking voltage circuit and said resonant circuit being connected in series, a second blocking voltage resistance-capacitance parallel circuit having one terminal thereof connected to the other end of the secondary of said input transformer, a capacitor connecting the other terminal of said second circuit to said cathode, a second rectifier, means to connect said serially-connected resonant network and first blocking voltage circuit through said second rectifier across said second blocking voltage circuit, said first blocking voltage circuit applying a bias across said second rectifier which is overcome by the oscillatory voltage developed across said resonant network solely during the existence of signal pulses to charge said second blocking voltage circuit thereby to apply a cut-off bias to said tube and deenergize said relay, a resistor connected between the negative terminal of said source and said cathode, and a third rectifier connected between said other terminal of said second blocking network and an intermediate point in said source, the voltage developed across said resistor during the conduction of said tube to charge said capacitor through said third rectifier being cut off on reception of signal pulses.
